UNITED STATES PATENT OFFICE.

WILLIAM LEWIS HENRY, OF ATLANTIC, PENNSYLVANIA.

POTATO-DIGGER.

SPECIFICATION forming part of Letters Patent No. 344,106, dated June 22, 1886.

Application filed February 9, 1886. Serial No. 191,350. (No model.)

To all whom it may concern:

Be it known that I, WILLIAM LEWIS HENRY, a citizen of the United States, residing at Atlantic, in the county of Crawford and State of Pennsylvania, have invented 5 a new and useful Improvement in Potato-Diggers, of which the following is a specification, reference being had to the accompanying drawings.

10 My invention relates to improvements in potato-diggers; and the novelty consists in the construction, arrangement, and combination of the several parts for service, substantially as hereinafter described, and specifically 15 pointed out in the claims.

In the drawings, Figure 1 represents a top plan view of a potato-digger embodying my improvement. Fig. 2 represents a side elevation, one of the wheels removed to show detail 20 of construction. Fig. 3 represents a longitudinal section on the line $x-x$ of Fig. 1.

Referring to the drawings, in which similar letters of reference denote similar parts, A designates the frame of the machine, consisting of broad side rails, a , that support the operative parts of the machine, and is mounted upon an axle, B, journaled at its opposite ends, b b' , in wheel's B B' , one of which, B' , operates as a driving-wheel to give motion to 25 the several operative parts of the machine, while the other merely fulfills the function of a bearing and supporting wheel. The former of said wheels, B' , is rigidly secured to the axle, preferably by a squared end, b^2 , formed 30 upon the end of the axle that takes or extends into a square aperture formed through the wheel, and is held in position therein by a pin, b^3 , that passes through an aperture formed through said square part b^2 , outside of 35 the wheel B' . The sides or rails a are spaced and held in parallel planes by transverse rails a' a^2 a^3 , that extend from one to the other of said side rails at the ends thereof. The former of said rails—to wit, a' a^2 —is located at the 40 forward end of the machine, each having their opposite ends formed into projecting studs that pass through apertures formed in the side rails to and into the lower ends of upright studs A' A^2 , placed at each side of the 45 machine, and connected at their upper ends by a transverse rail, a^4 .

a^5 designates braces that extend from the

upper ends of the uprights A' A^2 to points a^6 upon the upper surface of the rails a .

C designates a transverse rail that extends 55 from one to the other of the braces a^5 , near their lower ends, a^6 , and supports at one end the rear end of a board or plank, d, having a seat, D, secured to its upper surface for the 60 driver's use.

E designates the pole or tongue of the machine, the rear end, e, of which is provided with lugs or ears e' , that embrace the rail C at the middle thereof. The pole E extends forward through a slotted standard, E', the sides of 65 which are apertured to receive a pin, e^2 , by which the forward ends of the rails a and digger-forks between said rails are held at different desired distances from the ground. The forward end of the seat-board d rests upon a 70 rail, d' , that extends from the standard E' to the upright A' for its reception.

F designates the side rails of the digger tines or teeth, said rails being located within the rails a of the frame A, at the forward ends 75 thereof, and extending from the lower transverse rail, a^2 , rearwardly and upwardly, and held in position by an apertured bar or rail, f, the ends of which enter apertures f' , formed 80 in the side rails, a .

F' designates tines or teeth, preferably formed of steel rod or wire, the rear ends of each of which are provided with parts f^3 of less diameter than the body of the tines that enter and are secured in the apertures of the bar f, as 85 shown. The teeth extend forward beyond the rail a^2 , and when the machine is in motion pass below the potatoes, raising the same, together with the earth surrounding them, upon the upper surface of the tines or teeth F', between which the earth falls, while the continued forward movement of the machine carries the potatoes to a traveling carrier-belt, G, mounted upon and operated by rollers g g' , the former of which is journaled in the side 90 rails, a , near the rear transverse rail or bar, f, while the latter, g' , is journaled in said rails a in rear of the axle B.

g^2 g^3 designate rails that extend from one to the other of the rails a , between the rollers g g' , to support a scraper-plate, g^4 , the opposite ends of which impinge against the surfaces of the rollers g g' , to prevent dirt passing between the rolls and the belt thereon.

G designates an endless carrier-belt that is mounted upon and operated by the rolls g g', as above set forth.

g⁵ designates cleats secured transversely of the belt G to the outer surface thereof, and projecting at each edge of said belt, as shown at g⁶. The projecting ends g⁶ are provided with forwardly-projecting portions g⁷, which extend nearly to the next adjacent cleat, there-
10 by leaving openings between the ends of the cleats, (which project beyond the sides of the belt G,) through which the dirt may drop as it becomes loosened from the potatoes as they are carried rearwardly.

15 H designates an inclined chute having ends h secured to the side rails, a, at the inner surfaces and rear ends thereof, to receive the potatoes when they drop from the carrier and guide them to a box, H', at the rear end of
20 the chute.

h' designates a slot formed in the chute trans-
versely of the same, through which any re-
maining adhering earth may pass, while the
potatoes, being too large to pass through the
25 slot, pass over the same, and are delivered into
the box H'.

D⁸ designates a board held in slots g⁹ in
vertical position at the rear ends of the rails a.

Motion is imparted to the belt G in the fol-
30 lowing manner, viz: K designates a spur-gear
wheel mounted upon the axle near the wheel
B² and moving in unison therewith. K' designates a gear-pinion mounted upon the pro-
jecting journal of the rear roll, g', at one end
35 thereof, and engaging with and rotated by the
spur-wheel K.

The depth to which the digger-teeth enter
the earth is regulated and determined by the
pin e² and slotted standard E, as hereinbefore
40 stated, the pin e, after being adjusted to the de-
sired aperture in the standard E, resting upon
the upper surface of the pole or tongue.

To raise the forward end of the rails a, I
employ a lever, L, fulcrumed to the side of
45 the tongue within easy reach of the driver,
and a cord or chain, l, one end of which is se-
cured at l' to the lever, and passes thence over

a pulley, l², to an eye or staple, l³, secured in
the transverse rail a' of the frame A.

The operation of my device will be fully un-
derstood from the foregoing description, taken
in connection with the drawings attached
hereto.

I claim—

1. In a potato-digger, a frame, A, having 55
side rails, a, transverse rails a' a² a³, uprights
A' A², and braces a⁵, in combination with for-
wardly and downwardly projecting teeth or
tines F', located at the forward part of the
frame, carrier-belt G, chute H, and the axle 60
and wheels whereon the machine is mounted,
substantially as described.

2. In a potato-digger, a frame, A, having
side rails, a, transverse rails a' a² a³, uprights
A' A², provided with transverse rail a⁴ and 65
braces a⁶, in combination with rollers g g', jour-
naled in said rails a, belt G, mounted upon said
rollers and provided with transverse cleats g⁵,
teeth or tines F, secured to transverse rails f a²,
chute H, having slot h' and box H', and the 70
wheels B' B, substantially as described.

3. In a potato-digger, the frame A, having
rails a, transverse rails a' a² a³, uprights A' A²,
braces a⁵, transverse rail a⁴, and slotted stand-
ard E', in combination with a tongue, E, lever 75
L, cord l, and pulley l², substantially as de-
scribed.

4. In a potato-digger, a carrier-belt, G,
mounted upon rollers g g', and having trans-
verse cleats g⁵, in combination with a scraper-
plate, g⁴, located between and impinging upon
said rollers, substantially as described. 8c

5. In a potato-digger, a frame, A, having
uprights A' A², slotted standard E', provided
with transverse apertures and driver's seat D, 85
in combination with the lever L, its cord l,
pole or tongue E, axle B, and wheels B' B².

In testimony that I claim the foregoing as
my own I have hereto affixed my signature in
presence of two witnesses.

WILLIAM LEWIS HENRY.
